W. J. Sprague.

Attest:

John Schuman.

UNITED STATES PATENT OFFICE.

HARRY C. ALBEE, OF DETROIT, MICHIGAN.

MACHINE FOR FINISHING BROOM-HANDLES.

SPECIFICATION forming part of Letters Patent No. 348,878, dated September 7, 1886.

Application filed April 22, 1886. Serial No. 199,776. (No model.)

To all whom it may concern:

Be it known that I, HARRY C. ALBEE, of Detroit, in the county of Wayne and State of Michigan, have invented new and useful Improvements in Machines for Finishing Broom-Handles; and I do hereby declare that the following is a full, clear, and exact description thereof, reference being had to the accompanying drawings, which form a part of this specification.

This invention relates to a new and useful improvement in machines for finishing broom-handles; and the invention consists in the peculiar construction and arrangement of different devices, and in their combination into an operative machine, whereby the sticks after they are shaped by the turning-lathe are provided with a rounding head and with a saw-kerf (or a hole) near the butt-end of the stick for fastening the ends of the wire used in the further manufacture of the brooms.

To this end my machine contains the following elements: A feeding device, a clamping device for holding the stick while being operated upon, a saw on a swinging arbor for making a saw-kerf on the butt-end of the stick, (or, as an alternative, a boring-tool for boring a hole into the stick,) and a reciprocating cutter-head for rounding the head of the stick, the parts being constructed, combined and arranged to operate automatically, all as hereinafter described.

In the drawings, which accompany this specification, Figure 1 is a plan of my machine. Fig. 2 is a plan of the main shaft, showing the cams secured thereon and which actuate the different parts. Figs. 3, 4, 5, and 6 are cross-sections on the lines $x-x$, $y-y$, $z-z$, $v-v$, respectively. Fig. 7 is an elevation of the swinging saw-arbor and its operating connections. Fig. 8 is a plan of a boring-tool arranged in place instead of the saw shown in Fig. 1.

A is a bench or frame supporting all the different parts of my machine. B is a box or rack supported upon this bench. It forms a vertical well, C, of proper dimensions to hold in regular order a number of sticks, one on top of the other, as shown in the drawings. This well is open on top and bottom and may communicate on top with a hopper or other device for feeding the sticks into the well, or they may be fed by hand.

Transversely below the bottom of the well

are placed two or more horizontal sliding bars, D, which are held in suitable guides, E, secured upon the bench in rear of the well and prevent the sticks from falling out. These sliding bars are provided at their forward ends with rests a , which drop below the plane of the bar, and are suitably rounding to receive and support a stick. The bars D are reciprocatingly actuated in any convenient manner, such as shown in Fig. 4, wherein such reciprocation is obtained by the action of the cam G, lever F, and springs H, a duplication of this device actuating the other bar in precisely the same manner. The cams G are secured upon a shaft, J, which extends the entire length of the frame, and has a drive-pulley secured to one end thereof.

There are other bars stationarily secured opposite the bars D. They are provided with rounding rests b , so arranged that when the sliding bars D are in the position shown in Fig. 4 the rests a b are in proper juxtaposition to clamp a stick firmly between them, the springs H being free to operate with their tension.

K are levers, two or more of which are placed in such positions that when they are actuated by the cams L on the shaft J their free ends will knock the sticks off the rests a , as shown in Fig. 5.

M is a saw-arbor secured in suitable bearings upon a frame, N, which swings on a vertical pivot-pin, c, upon a suitable bed-plate.

The operation of swinging the saw-frame is for the purpose of approaching the saw O toward the butt-end of a stick whenever a stick is presented for operation, as hereinafter described.

The devices for swinging the saw-frame at the proper intervals may be arranged in any convenient manner—such as shown in the drawings—wherein a cam, P, on the shaft J, actuated, in connection with a spring, Q, a bell-crank lever, R, which latter is pivotally connected with the lever S and oscillates on the pivot c, said motion being participated in by the saw-frame by reason of its engagement with the oscillating lever S at d .

The saw-arbor has a suitable pulley, to which motion is given by a belt from an overhead shaft, so that the swinging of the saw-frame will not affect the tightness of the belt.

The saw O is dished so as to cut a kerf of

such nature into the stick that if the end of the broom-wire is inserted it will hold fast; but as this saw-kerf is not universally used for such purpose I make suitable provision to use, if desired, instead of the saw a boring attachment, which makes a small hole through the butt-end of the stick for fastening the end of the broom-wire. This boring attachment may be arranged as shown in Fig. 8, where in S is a mandrel carrying a suitable bit and revolving in a sliding frame, which, by means of suitable intermediate connection with the cam G, such as shown hereinafter for the mandrel T, is projected toward the butt of the 15 stick and withdrawn when the hole is bored.

The opposite end of the machine is provided with a revolving mandrel, T, which carries a cutter-head, U, with suitable knives arranged to round off or pare the end of the 20 stick which is presented to it. This mandrel is revolved by a belt from an overhead shaft, and it is journaled in a frame, Y, which slides on the bed-plate.

The sliding of the frame Y and its mandrel 25 from and toward its work at the proper intervals of time is produced by a cam, V, on the shaft J. This cam, in connection with the spring W, actuates the bell-crank Z, which, as shown in Fig. 6, in turn actuates the frame Y. 30 It will be seen from the foregoing description that all the operative parts are controlled in their action by cams secured on the shaft J, and these cams are so arranged as to operate the machine in the following manner: The 35 cams G control the feed by retracting the sliding bars D and permitting the feeding down of the sticks in the well onto the rests a. The springs H, in projecting the sliding bars again, force the latter to carry out the lowest 40 stick from underneath, and to carry it forward and clamp it between the rests a b. While the stick is thus held the cams P and V perform their action, the former swinging the saw-frame (or projecting the boring attachment) toward the butt of the stick, and the latter projecting the mandrel which carries the rounding-off cutter-head, these parts, after this operation, being retracted again by 45 springs acting in connection with these cams. Now, the cams G operate again to retract the sliding plates, but before this movement is finished the cams L actuate the knockers K to throw the finished stick off the bearings a, thus permitting the sliding plates to withdraw 50 empty and project with a new stick again. The endwise displacement of the sticks while being operated upon by the rounding-off cutter-head, is prevented by an end plate, X.

The operation of the machine is perfectly 55 automatic, and permits of being run with a considerable speed, finishing a stick at every revolution of the shaft J.

What I claim as my invention is—

1. A machine for the purpose described and having the following characteristics: a feed-rack from which the sticks are fed seriatum by gravity, sliding bars under the feed-rack provided with depressed rests, onto which the lowest stick is dropped, stationary bars arranged adjacent to and beneath the discharge end of said rack and constructed to act in connection with the sliding bars to clamp each stick, a saw or boring-tool at one end of the machine and constructed to be thrown into and out of contact with each stick, a sliding mandrel at the opposite end of the machine and provided with a cutter-head for rounding the head of each stick, and an extractor device for removing each stick after it is operated on, all arranged to operate substantially in the manner described. 70 80

2. In a machine for the purpose described, the combination of the following elements: the rack B, the sliding bars D under said feed-rack, and having rests a, the stationary plates I, arranged adjacent to and beneath said rack, and having rests b, and actuating mechanism for the bars D, such as the cams G, levers F, and springs H, all arranged to operate substantially as described. 90

3. In a machine for the purpose described, the combination of the racks B, the sliding bars D, having rests a, the stationary bars I, having rests b, and actuating devices for the sliding bars D, consisting of the shaft J, cams G, levers F, and springs H, the latter being arranged to act with their tension in clamping the sticks, substantially as described. 95

4. In a machine for the purposes described, the combination, with the sliding bars D and 100 stationary bars I, arranged to clamp a stick, as described, of a device for forming a place in the butt-end of the stick to secure the broom-wire, said device being carried by a frame arranged to move toward and from the clamped stick, and of the mandrel T, having a cutter-head, U, and carried in a sliding frame, Y, arranged to move toward and from the head of the clamped stick, all substantially as described. 110

5. In a machine for the purpose described, in combination with the shaft J, carrying the cams P, G, L, and V, a kerfing or boring tool actuated by the cam P, a rounding-off cutter-head actuated by the cam V, a feeding device having sliding bars D, actuated by the cams G, and an extractor device having knockers K, actuated by the cams L, all the parts being constructed and arranged to operate, substantially as described. 115
